CLAIM

We claim the ornamental design for piping of a sports equipment bag, as shown and described.

DESCRIPTION

FIG. 1 is a side perspective view of a sports equipment bag; FIG. 2 is a first side view of the sports equipment bag of FIG. 1;

FIG. 3 is a second side view of the sports equipment bag of FIG. 1;

FIG. 4 is a top view of the sports equipment bag of FIG. 1; FIG. 5 is a first end view of the sports equipment bag of FIG. 1;

FIG. 6 is a second end view of the sports equipment bag of FIG. 1; and,

FIG. 7 is a bottom view of the sports equipment bag of FIG. 1.

The ornamental design that is claimed is shown in solid lines in the drawings. The broken (dashed) lines shown in FIGS. 1 through 7 are included for the purpose of illustrating environmental elements only and form no part of the claimed design.
